UNITED STATES PATENT OFFICE.

PAUL N. WAGGENER, OF MEMPHIS, TENNESSEE.

FINGERPRINT APPARATUS.

Application filed January 4, 1927. Serial No. 158,902.

This invention relates to containers and more particularly to holders for retaining a sheet or card while recording thereon finger print impressions.

The holders heretofore employed to receive and fixedly maintain a sheet or card for the recording of finger prints have been of an elaborate structure, difficult and expensive to manufacture. In operation, these holders, because of their complexity, easily get out of order and are difficult to repair. In addition to these disadvantages, these holders involve time consuming methods of operation, for the insertion of the card or sheet and any subsequent change of position necessitates an adjustment of the holder.

An object of my invention is to provide a holder, inexpensive and easy of construction.

Another object of my invention is to provide a holder that is simple and durable in structure.

Another object of my invention is to provide a holder that is simple in operation.

A still further object of my invention is to provide a holder wherein the cards or sheets are securely maintained when desired, yet permitting movement therein of the recording medium without any adjustment of the holder.

My invention consists in a device which fixedly holds the card or sheet when desired and at the same time allows the insertion, withdrawal, or change in position of the sheet or card without adjustment of the device, and provided with means to guide the card or sheet without positioning the same in the holder.

In the accompanying drawings, in which the same parts have similar numerals:

Figure 1 is a perspective view of the holder containing a card therein;

Fig. 2 is a cross sectional view of the holder along the line 2—2 of Fig. 1;

Fig. 3 is a cross sectional view along the line 3—3 of Fig. 2.

The holder is designed to retain a card or sheet 1 having designated spaces 4 thereon for receiving the impressions of the respective fingers, the holder comprising a block 5 upon two perpendicular faces 6 and 7 of which the card or sheet rests. The junction of the two faces 6 and 7 is gradually rounded, as at 8. On the side edges of the block, and extending along both faces are the continuous strips 9, upon which are fastened wider strips

11 overhanging inwardly the strips 9. The strips 11 are so spaced from the block that buckling or crumpling of the card or paper is prevented.

While I have shown two strips running the length of the side, it is, of course, obvious that the same result might be obtained by other means, such as one strip with a flange corresponding to the strip 11, or a single strip attached to the block and bent to permit the interposition of a card or sheet between the block and the strip. Other strips 12 connect the ends of the side strips. In the drawings the strips 12 are shown as part of the strips 11, but of course they may be separate and attached securely to the side strips.

It will be seen that there is a space 13 between the strips 11 and 12 and the contact faces of the block, permitting the insertion of a card or sheet and its passage through the holder, the strips 9 serving as guides. The strips 12 and the overlapping portions of strips 11 maintain the card or sheet in flat contact with the block, yet not seriously impeding passage of the sheet over the faces 6, 7 and 8.

The curvature indicated by 8 provides a surface over which the recording medium may easily slide. This curved section permits of a complete impression of that portion of the finger desired, whether a so called plain or rolled impression, for there can be effected a longitudinal rolling of the finger in which each segment is impressed on the recording medium. It is also to be noted that by properly adjusting the sheet there is prevented any impression of the finger below the desired point on the card.

The card or sheet, on being forced through the holder, offers resistance to the bending action at 8, and after insertion tends to assume its original flat and straight form. This tendency, however, is prevented by the strips 12, as well as the strips 11. As the card or sheet tends to resume its normal shape, it is forced against the strips 12, as shown at 14, forming frictional contacts which serve to fixedly maintain the sheet in any desired position.

While the holder is especially designed for cards on which successive prints are to be longitudinally imposed, it may be used where a card or sheet has space for only one print. And again, while the holder is designed for a card or sheet of a certain width, it does not

preclude the use of a recording medium of less width, for the frictional points 14 will securely hold the card in position during the printing.

5 While I have shown and described the preferred embodiment of my invention, I wish it to be understood that I do not confine myself to the precise details of construction herein set forth, by way of illustration, as it is 10 apparent that many changes and variations may be made therein, by those skilled in the art, without departing from the spirit of the

invention, or exceeding the scope of the appended claim.

I claim:

15 A card holder comprising a block having a horizontal face and a vertical face, an arcuate surface at the juncture of said faces, a metal guard mounted upon said block overlying the edges and exposing a portion of said faces 20 and arcuate surface.

In testimony whereof I affix my signature.

PAUL N. WAGGENER.
